FLAT IRON HOLDER

Frederick Marx, Sr., 2205 N. 7th Ave., Lake Worth, Fla.
Filed June 13, 1961, Ser. No. 116,760
15 Claims. (Cl. 248—117.2)

This invention is an improvement in flat iron holders or the like and is of simple, novel and efficient construction; and the principal objects of the invention are to provide a flat iron holder consisting of a back plate adapted to be pivotally mounted on an ironing board and carrying tynes fixedly secured thereto, said back plate also adjustably comprising a body portion having a bottom and opposite sides, thereby rendering it possible for the holder to receive flat irons or the like of various thicknesses, the back plate carrying the tynes also being adjustable in spaced relation to the body of the holder; also to provide a novel flat iron holder in which the design of the tynes offers a better means of securing an easier placement of the iron into the holder; also to provide a novel flat iron holder embodying novel hook-like supporting legs or feet at the front bottom of the body portion, thus providing a more simplified and better means of supporting the holder when stored in a vertical position, the legs or feet forming hooks which may be readily hung over a nail or the like to hold the device on a vertical wall when not in use.

Other minor objects of the invention will be herein-after set forth.

I will explain the invention with reference to the accompanying drawing, which illustrates one practical embodiment thereof, to enable others to adopt and use the same; and will summarize in the claims the novel features of constructions, and novel combinations of parts, for which protection is desired.

In said drawing:

FIG. 1 is a top perspective view of my novel flat iron holder.

FIG. 2 is a perspective view similar to FIG. 1 of the rear end of the holder but showing the back plate separated from the body portion of the holder to better illustrate the means for adjustably mounting the body portion on the back plate.

FIG. 3 is a view similar to FIG. 1 showing the holder applied in upended position to an ironing board.

FIG. 4 is a view similar to FIG. 3 but showing the holder disposed flat upon the ironing board.

As shown in the drawing, my novel iron holder preferably comprises a back plate 1 which preferably comprises a strip of metal or other durable material, of length somewhat greater than the width of the flat iron to be held in the holder, the back plate 1 having both ends flanged forwardly as at 1a, and each flange being provided with transversely spaced aligned holes 1b for the purpose hereinafter set forth.

The back plate 1 supports a pair of spaced tynes, each being symmetrical with respect to the other, and consisting of flattened wire or other loops 2 and 3 having substantially parallel spaced runs, the outer portions of which loops extend normal to the back plate 1 as shown, and the intermediate portions being bent as at 2a, 3a, respectively, to underlie the back plate 1, the same being secured thereto by spot welding or the like so as to be fixedly mounted thereon.

The rearmost portions of the loops 2 and 3 are bent as at 2b, 3b, to extend outwardly beyond the flange portions 1a of back plate 1 as shown, the outer ends of the bent portions 2b, 3b, forming eyes 2x, 3x, disposed parallel with the plane of the back plate 1 through which eyes 2x, 3x, an elastic or other cord 4 may be passed to hingeably connect the back plate 1 with the top of an

2

ironing board B, whereby the back plate 1 may be swung to lie parallel with the board B, as shown in FIG. 3, or swung into position normal to board B, as shown in FIG. 4.

5 Instead of cord 4 passing through the eyes 2x, 3x, the eyes might obviously receive hooks (not shown) at the ends of the elastic cord 4 in the usual manner.

It is noted that when the back 1 is normal to board B, as shown in FIG. 4, the bent portions 2b, 3b of the tynes 10 will maintain the bottom of the back plate 1 spaced from the cover of the ironing board B to prevent scorching thereof by a hot iron held in the holder.

The body of the holder consists of a bottom plate 5 which has its sides flanged as at 5a, the flanges 5a being 15 provided with perforations 5b, respectively, adapted to register with the perforations 1b in the flanges 1a of the back plate 1, whereby a screw 6 may be inserted through any of the registering holes 5b, 1b, and thereby adjust the bottom plate 5 towards or from the cover of ironing board 20 B when the holder is in the position shown in FIG. 4, and simultaneously to adjust the bottom 5 towards or from the tynes 2, 3, fixedly carried by the back plate 1, thereby adjusting the holder to suit flat irons of different heights or thicknesses, while at the same time preventing the heat 25 of the iron from scorching the cover of the ironing board B.

As shown, the forward ends of the flanges 5a are preferably rounded as at 5c and terminate short of the outer end of the bottom plate 5, which outer end is curved 30 downwardly as at 5d and has its outer edge turned back on itself as at 5e to stiffen the same, the curved portion 5d facilitating entry of the heel of the flat iron into its position in the holder.

In order to further support the front end of the bottom 35 plate 5, I provide novel supporting legs or feet consisting of a length of wire 7 which extends across the bottom plate 5 on the underside thereof and which is preferably spot welded or otherwise secured thereto, the ends of the wire 7 extending beyond the sides of the bottom plate 40 5 and being offset downwardly as at 7a, the outer ends thereof being further bent rearwardly as at 7b, so that when the holder is in the position shown in FIG. 4, the bent portions 7b will further support the outer end of the bottom plate 5 upon the ironing board B assisted 45 by the curved portion 5d at the outer end of the bottom.

The legs or feet 7b not only assist in supporting the weight of the iron in the holder when the holder is in the position shown in FIG. 4, but the legs 7b also serve as hooks for conveniently hanging the holder on a nail 50 or the like on a vertical wall to support the holder when not in use, the legs 7b then serving as hooks when so supporting the holder.

Thus I have provided a holder in which the bottom is 55 adjustable with respect to the tynes permitting any flat iron or the like to be held therein regardless of its height or thickness, for obviously a thick flat iron would require the tynes 2 and 3 to be further spaced from the bottom 5 than in the case of a relatively thin flat iron; also the arrangement is such that the tynes offer a better means of securing 60 and easier placement of the iron into the holder; also the design of the legs 7b or supporting means at the front bottom of the holder offers a more simplified and better means of supporting the holder when stored in a vertical position on a nail or the like by hooking the bent ends 65 7b of the legs over a nail or other supporting means.

I do not limit my invention to the exact form shown in the drawing, for obviously changes may be made therein within the scope of the claims.

I claim:

70 1. A holder for flat irons or the like, comprising a back plate of greater width than a flat iron to be supported

and having flanges at each end; spaced tynes mounted on the back plate extending normal thereto and offset from one edge thereof, said tynes having portions underlying and secured to the back plate and extending beyond the opposite edge thereof; said tynes having eyes extending laterally beyond the said flanges for receiving a cord for mounting the holder on an ironing board; and a body portion comprising a bottom plate having sides adapted to contact the flanges of the back plate; means for adjustably connecting the sides and flanges together; and supporting feet mounted on the bottom plate extending beyond the sides thereof and being offset from the bottom.

2. In a holder as set forth in claim 1, said tynes comprising flattened wire loops having substantially parallel spaced runs, said loops having intermediate bends forming the portions underlying and secured to the back plate, and the inner end portions of the loops having further bends forming the said eyes and maintaining the bottom plate of the holder spaced from the ironing board when the holder is swung downwardly thereon.

3. In a holder as set forth in claim 1, the forward ends of the sides terminating in advance of the outer end of the bottom plate; and said feet comprising a wire secured to the underside of the bottom plate, the outer ends beyond the sides being offset below the plane of the bottom plate, and being further bent beyond the offsets to form hooks.

4. In a holder as set forth in claim 1, said connecting means comprising fasteners engaging registering perforations in the flanges and sides whereby the bottom plate will be adjustable with respect to the tynes and an ironing board.

5. A holder for flat irons or the like, comprising a back plate of greater width than a flat iron to be supported and having flanges at each end provided with a series of aligned transversely spaced perforations; spaced tynes mounted on the back plate extending normal thereto and offset from one edge thereof, said tynes having portions underlying and secured to the back plate and extending beyond the opposite edge thereof, and having eyes extending laterally beyond the said flanges for receiving a cord for mounting the holder on an ironing board; and a body portion comprising a bottom plate having sides adapted to contact the flanges of the back plate and having perforations adapted to register with those in the flanges; removable means for adjustably connecting the sides and flanges together through any of said registering perforations; and supporting feet mounted on the bottom plate extending beyond the sides thereof and being offset from the bottom.

6. In a holder as set forth in claim 5, said tynes comprising flattened wire loops having substantially parallel spaced runs, said loops having intermediate bends forming the portions underlying and secured to the back plate, and the inner end portions of the loops having further bends forming the said eyes, and maintaining the bottom plate of the holder spaced from the ironing board when the holder is swung downwardly thereon.

7. In a holder as set forth in claim 5, the forward ends of the sides being rounded and terminating in advance of the outer end of the bottom plate; and said feet comprising a wire secured to the underside of the bottom plate, the outer ends beyond the sides being offset below the plane of the bottom plate, and being further bent beyond the offsets to form hooks.

8. In a holder as set forth in claim 5, said connecting means comprising screws with nuts whereby the bottom plate will be adjustable with respect to the tynes and the ironing board.

9. A holder for flat irons or the like, comprising a back plate of greater width than a flat iron to be supported and having flanges at each end provided with a series of aligned transversely spaced perforations; spaced

5 tynes mounted on the back plate extending normal thereto and offset from one edge thereof, said tynes having portions underlying and secured to the back plate and extending beyond the opposite edge of the back plate, and having eyes for receiving an elastic cord for mounting the holder on an ironing board, said eyes extending laterally beyond the said flanges; and a body portion comprising a bottom plate having sides adapted to contact the flanges of the back plate and having perforations adapted to register with those in the flanges; removable means for adjustably connecting the sides and flanges together through any of said registering perforations; the outer end of the bottom plate being curved downwardly and adapted to seat upon an ironing board when the holder is swung downwardly thereon; said outer end having a stiffening rib; and supporting feet mounted on the bottom plate extending beyond the sides thereof and being offset from the bottom a distance substantially equal to the amount of curvature of the outer end of the bottom plate.

10 10. In a holder as set forth in claim 9, said tynes comprising flattened wire loops having substantially parallel spaced runs, said loops having intermediate bends forming the portions underlying the back plate and being secured thereto, and the inner end portions of the loops having further bends forming the said eyes, and maintaining the bottom plate of the holder spaced from the ironing board when the holder is swung downwardly thereon.

15 11. In a holder as set forth in claim 9, the forward ends of the sides being rounded and terminating in advance of the curved outer end of the bottom plate; and said feet comprising a wire secured to the underside of the bottom plate, the outer ends beyond the sides being offset to suit the curvature of the bottom plate, and being further bent to form hooks beyond the offset portions.

20 12. In a holder as set forth in claim 9, said removable connecting means comprising screws with nuts whereby the bottom plate will be adjustable with respect to the tynes and the ironing board.

25 13. A flat iron holder or the like, comprising a back plate of greater width than a flat iron to be supported, a bottom plate, and side plates; spaced tynes comprising flattened wire loops each having substantially parallel spaced runs mounted on the back plate extending normal thereto and offset from one edge thereof, said tynes having intermediate bends underlying and secured to the back plate and extending beyond the opposite edge of the back plate, and having further bends at their inner ends forming eyes extending laterally beyond the said flanges for receiving an elastic cord for mounting the holder on an ironing board; and the outer end portion of the bottom plate being curved downwardly and adapted to seat on an ironing board when the holder is swung downwardly thereon.

30 14. In a holder as set forth in claim 13, the forward ends of the sides being reduced in width and terminating in advance of the curved outer end portion of the bottom plates.

35 15. In combination with a holder as set forth in claim 13, supporting feet comprising a wire secured to the underside of the bottom plate adjacent its outer end and extending beyond the sides thereof, the outer portions of the wire beyond the sides being offset to suit the amount of curvature of the bottom plate, and the outer ends thereof being further bent to form hooks disposed beyond the offset portions.
